(57) **CLAIM**

The ornamental design for a golf training aid, as shown and described.

DESCRIPTION

FIG. 1 is a top, front, right-side perspective view of a golf training aid;

FIG. 2 is a top, front, left-side perspective view thereof;

FIG. 3 is a bottom, back, left-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof;

FIG. 9 is a bottom view thereof; and,

FIG. 10 is an enlarged front view of the area marked 10 in FIG. 4.

The dash-dash broken lines depict portions of the golf training aid that form no part of the claimed design. The dot-dash broken lines depict the boundaries of the detail view and form no part of the claimed design.

1 Claim, 10 Drawing Sheets
